(57) CLAIM

The ornamental design for a beverage container, as shown and described.

DESCRIPTION

FIG. 1 is a front perspective view of a beverage container according to the present invention;

FIG. 2 is a front view of the beverage container of FIG. 1; FIG. 3 is a rear view of the beverage container of FIG. 1; FIG. 4 is a left side view of the beverage container of FIG. 1;

FIG. 5 is a top view of the beverage container of FIG. 1; FIG. 6 is a bottom view of the beverage container of FIG. 1; FIG. 7 is a perspective view of the beverage container of FIG. 1 but without the lid;

FIG. 8 is a front view of the beverage container of FIG. 7; FIG. 9 is a side view of the beverage container of FIG. 7; and,

FIG. 10 is a top view of the beverage container of FIG. 7. The rear view of the beverage container is the same as the front view and the left side view is the same as the right side view.
